UNITED STATES PATENT OFFICE.

FRANK ZALESKI, OF CAMBRIDGE, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-STITCHING MACHINE.

1,318,430.

Specification of Letters Patent. Patented Oct. 14, 1919.

Application filed April 11, 1916. Serial No. 90,309.

To all whom it may concern:

Be it known that I, FRANK ZALESKI, a subject of the German Emperor, residing at Cambridge, in the county of Middlesex and State of Massachusetts, have invented certain new and useful Improvements in Buttonhole-Stitching Machines, of which the following is a specification, reference being had therein to the accompanying drawing.

10 This invention relates to buttonhole stitching machines, and more particularly to the well-known "Reece" type of button-hole stitching machine.

The Reece buttonhole stitching machine usually both cuts and stitches the buttonhole slit, the cutting preferably preceding the stitching. This type of machine usually employs a movable plate or clamp by which the work is held and fed, there being two or more stages in the feeding movement, including the slow or intermittent movement of the work during stitching and the movement between the cutting position and the stitching position of the work. One usual arrangement is that, upon pressing the control lever which starts the machine, the cutting of the slit is first effected, this being followed by a rapid advance of the work from the cutting place forwardly to where the stitching is to commence, a general control cam thereupon throwing out the connections performing these operations and throwing in the stitching devices, which stitch around the margin, accompanied by a suitable slow feed of the work clamp and work until the circuit of the buttonhole has been completed, whereupon the stitching devices and feed are thrown out of engagement and the clamp caused to rapidly move back to initial position, upon which all driving is caused to cease and the machine brought to a stop with the needles out of the work and the cutting and other parts in readiness for a new operation. It has been usual to employ the main cam member not only for effecting the described control, but also for effecting the movements of the work clamp during the different stages in the operation of producing a buttonhole. Two quite separate power belts and driving connections have been employed, the first more rapid in operation than the second, and the two thrown into and out of operation alternately for actuating the main cam and the other

parts under control of the cam itself. Certain complications resulted from this duplex drive system, which has not been as entirely effective as desirable, nor absolutely invariable in action.

The main object, therefore, of the present improvement is to afford a buttonhole stitching machine in which the driving or operating mechanism is more simple and effective than heretofore and invariable in the uniformity of its action.

More especially an object hereof is to dispense with the duplex driving system and to provide that a single driving part, pulley or belt, which is constantly running under power, may serve to bring about all of the operations of the machine, including the cutting, the jumping movement following the cutting, the stitching and the feeding movement accompanying the stitching and the subsequent final jump movement to initial position, all in the predetermined order and harmony.

It is a more detailed object hereof to secure the results mentioned by means of a plurality of quick-acting clutches and stops exactly and automatically controlled, so that each successive phase or stage of the stitching operation is completed and the parts involved therein brought to a stop prior to the commencement of the next phase or stage of the operation. Further and more detailed objects and advantages of the present invention will be elucidated in the hereinafter following description of one form or embodiment thereof, and additional advantages will be apparent to those skilled in the art.

In the accompanying drawings, Figure 1 is a right elevation of the major portion of a buttonhole stitching machine of the Reece type embodying the present improvements.

Fig. 2 is a detached right elevation of the finger lever for starting the machine into operation.

Fig. 3 is a right elevation upon a larger scale of certain of the particular driving and stopping parts involved in this invention, certain parts shown in Fig. 1 being omitted herefrom for clearness.

Figs. 1, 2 and 3 show the parts in their normal or stopped position occupied by them when the machine is not in operation.

Fig. 4 is a view similar to Fig. 3, but at a

stage after the depression of the start lever and as the machine is about to start into movement.

Fig. 5 in a similar view shows the same parts at a later stage, the stitching and the slow feed accompanying it having commenced.

Fig. 6 is a central section on the plane 6-6 of Fig. 3.

10 Fig. 7 is a top plan view of the parts shown in the other figures.

Fig. 8 is a right elevation, partly in section on the plane 8-8 of Fig. 11, of a clutch device on the worm shaft by which the latter 15 is rapidly advanced.

Fig. 9 is a similar elevation, partly in section on the plane 9-9 of Fig. 11, of a clutch on the worm shaft by which the latter is advanced slowly during stitching.

20 Fig. 10 shows the same parts viewed from the left of Fig. 9.

Fig. 11 is a vertical section taken on the plane 11-11 of Fig. 7.

Referring first to some of the usual parts 25 of the buttonhole stitching machine, a bed 20 is employed, above and below which are the various mechanisms. Above the bed is the usual overhanging arm 21 and below it a casing 22, containing the control disk or 30 general cam 23. Above the front portion of the bed is part of the stitching mechanism, including the upper needle 24, and there may be a co-operating under stitching mechanism 25 beneath the bed. The buttonhole 35 slit cutter is shown in the form of an arm 26 above the bed having a downward extension 27, which is engaged at suitable times by a special cam or elevation 28 on the control disk 23 for actuating the cutter. Associated with the stitching and cutting devices is a clamp plate 29 which supports clamp members 30. This device 29, 40 30 is adapted to be bodily moved for the purpose of shifting or feeding the work, 45 namely, by means of a bar or frame 31 beneath the bed, the same provided with a cam roll 32 engaging a groove 33 in the control disk 23.

The control disk or cam 23 is a driven 50 part of the machine, and it comes to a stop at the end of each cycle of operations. This member not only controls the time of cutting and brings about the proper feeding of the work clamp and work, but serves, as will 55 hereinafter more fully appear, to control the driving and stopping devices or clutches by which the power is transmitted to the disk and to the stitching and other mechanisms.

60 As a convenient mode of transmitting power to the disk 23 and at the same time for reducing the rotary speed of the driving parts, a worm 34 engages the toothed periphery of the disk, this worm being carried

on a shaft 35 with which the disk therefore 65 always moves in time. The worm shaft 35 is below the bed at the rear.

A second shaft 36 considerably above the bed is a part of the train of connections for 70 operating the stitching means, and may conveniently be termed the stitching shaft. This is rotated at high speed during stitching and acts through the needle lever 37 and other stitching connections to operate the needles and associated members.

The connections by which the rotation of the stitch shaft 36 are caused to actuate the worm shaft 35 may include an eccentric 38 on the stitch shaft, engaged by the yoke arm of a bell crank 39, the rearwardly 80 extending arm 40 of which (see Fig. 1) is connected by rod 41 with an arm 42, by which is actuated a friction clutch device 43, (see Figs. 9 and 10) mounted directly on the worm shaft 35. By these connections the 85 rotation of the stitch shaft causes the worm shaft to rotate intermittently, giving a step-by-step advance to the control disk 23 and a corresponding feed to the work during stitching.

The friction clutch device 43, just mentioned, is of a type which is employed at four different places in the present illustrated machine. The principle of this is that an eccentric operates to wedge a gripping portion against the rim of the device to effectively clutch them together. Thus, the eccentric 44, which is rigid with the arm or extension 42, loosely surrounds the shaft 35, while the rim or drum member 45 is fast upon the shaft. A ring or strap 46 surrounds the eccentric 44, and at one side is suitably extended to afford a grip portion 47, which lies snugly against and is adapted to be wedged against the rim 45. A spring 48 is arranged between pins on the eccentric and on the strap, respectively, tending to pull the latter in such direction as to throw and maintain the grip 47 into a suitable, comparatively light contact with 100 the rim 45.

Swinging the arm 42 or turning the eccentric 44 clockwise in Fig. 9 causes the grip 47 to bind more forcibly against the rim so as to carry the shaft 35 clockwise. At the 115 same time, the engagement of the grip and the rim being normally only a frictional engagement, it is obvious that the shaft may be turned clockwise by some other means, if desired, although the eccentric 44 be stationary and the clutch 43 inoperative. This clutch is supposed to operate only to effect intermittent feed during the stitching, and at certain other times when the stitching is not proceeding the clutch is inoperative and the worm shaft is rotated by other connections, as will more fully appear.

As the link or rod 41 moves up and down

carrying the arm 42 with it, the worm shaft 35 is advanced clockwise as follows. The upward movement of the arm 42 turns the eccentric 44 so as to bind the grip 47 against the rim of drum 45. The gripping is immediate, and the shaft partakes of the movement. When the arm 42 reaches the top of its stroke and moves downwardly, the eccentric 44 turns counterclockwise, thus tending to release the grip from the rim and causing cessation of driving engagement, so that the parts are simply restored to position without reversely rotating the shaft. The spring 48 pulls the grip 47 in the counterclockwise movement.

This action of operatively engaging and disengaging the grip with the rim is instantaneous, so that there is no lost motion or variation in action. To render the certainty more certain, the following device may be added. Mounted on the arm 42 is a small rocking lever 49, (see Figs. 9 and 10). The inward arm of this lever projects toward the shaft 35 and is engaged between two pins 50 mounted on the strap 46. By this arrangement the lever, if it is swung, may relatively throw the strap and the grip 47 either toward or from locking position. The outer end of the lever 49 moves upwardly and downwardly with the swinging of the arm 42. A pair of contact pins 51 are located at the upper and lower ends of the path of movement of the lever 49, these pins being adjustably secured on bracket 52. By this arrangement the lever 49 operates just as the ascending arm 42 reaches the end of its driving stroke to throw the strap and grip away from gripping position against the resistance of spring 48. This is accomplished by the lever striking the upper pin 51, which relatively forces downwardly the outer lever arm, thus lifting the inner lever arm and slightly turning the strap 46 clockwise. When the arm moves downwardly at its idle stroke, the extreme limit of its movement is accompanied by a contact between lever 49 and the lower pin 51, which assists the spring 48 in throwing the grip 47 into driving engagement with the rim. Thus has been described a friction feed mechanism for the worm shaft, one friction member of which is positively moved into and out of gripping engagement with the other.

This completes the description of the illustrated feed connections by which the stitching shaft 36, when in operation, serves to slowly advance the worm shaft 35 and the disk or main cam 23.

It is deemed important, whether or not the worm shaft rotation be continuous during stitching, that the driving connections be such that, when inoperative, they do not lock the worm shaft 35, but leave it free to be advanced otherwise. As will be seen

later, a device is employed which locks the shaft 35 against possible reverse movement during the oscillations of the described intermittent feed connections.

At the righthand end of the stitching shaft 36 is shown a hand wheel 54 by which the shaft may be turned at will.

Next will be described the driving belt and pulley, which are supposed to run continuously and by which power is communicated for all purposes of the machine; and thereafter a double clutching arrangement by which at times the stitching shaft 36 may be driven and at other times connections for causing a shifting of the work when stitching is not proceeding. For convenience I will use the term "feed" to designate the advance of the worm shaft and main cam and work clamp, which is effected during stitching and from the stitching shaft, whereas the movement of the parts when the clamp shifts from initial or cutting position to stitching position and reverse I will designate a "jump". The latter movement may be, and preferably is, of much greater speed than the feed movement, so as to minimize loss of time between the cutting and stitching operations.

Mounted for convenience on the stitching shaft 36, but loose thereon, is the continuously running belt pulley 60, associated with which is the stitching clutch at its left (Fig. 6) and at its right the clutch which actuates connections for causing the jumping movements of the work. The pulley is shown as having a hub 61. The pulley is formed with concentric recesses at its two sides, so that near the periphery at each side is an inwardly facing surface or rim 62 at the right and 63 at the left. These rims take part in the clutching operations and correspond with the rim 45 in clutch device 43 of Fig. 9.

The stitching clutch serves at the proper times to connect the pulley 60 with the stitching shaft 36, as seen in cross-section in Fig. 6, and in dotted lines in right elevation in Fig. 5.

The clutch comprises an eccentric 64. This is keyed upon the shaft 36, the pulley 60 and rim 63 being loose thereon. This arrangement is the reverse of that shown in Fig. 9. Surrounding the eccentric 64 is the strap 65 having the extension or grip portion 66 capable of binding against the rim 63. A circularly arranged coil spring 67 tends to hold the grip 66 lightly in contact with the rim 63.

The gripping action depends upon the relative positions of the eccentric and strap, and to control their relative positions a finger 69 is extended radially outward from the strap, and a finger 70 is extended radially outward from the eccentric.

When the fingers 69, 70 are unrestrained, 130

as in Fig. 5, the spring 67 holds the grip against the rim, and, as the rim and pulley are continuously rotating counterclockwise, this serves to drive the grip, the strap, the 5 eccentric and the stitching shaft, the fingers 69, 70, of course, rotating with them.

Before the shaft can be stopped, it must be uncoupled by removing the grip from the rim or relieving the pressure, and this may 10 be accomplished by moving the finger 69 relatively backward, so that, as compared with Fig. 5, the fingers will assume the position of Fig. 3, in which it will be seen that the grip is slightly retracted from the rim. 15 This uncoupling, and also the stopping of the stitching shaft by impact, are both effected by means of a non-rotating dog 72, shown operative in Fig. 3, and retracted or inoperative in Fig. 5. By swinging the 20 dog inward, as in Fig. 3, the fingers 69, 70 strike it. First the finger 69 strikes it, thus disengaging the clutch, the finger 70 then striking it, thus stopping the shaft, and the parts being held in this position 25 until the dog 72 is subsequently swung outward to cause the shaft to resume rotation.

A braking device 71 is shown in the form of a plunger 71, pressed powerfully inward by an adjustable spring. This is initially 30 adjusted so as not to contact the whirling fingers 69, 70. When, however, finger 69 comes up against dog 72, the continued rotation of the eccentric tends to force the finger outward, and the brake device 71 by 35 spring yielding resistance to this movement imposes a braking force tending to slow the shaft and reduce the shock which occurs when the other finger 70 impacts against the dog 72. 40 The swinging dog or lever 72 is shown rigidly mounted on a shaft 73, this shaft having a second rigid arm 74, the end of which rests upon the top of a cam pin 75, which extends downwardly to where it may 45 coöperate with a cam or elevation 76 formed on the main cam disk 23. The operation of the cam portion 76 is to lift the pin 75 and arm 74 so as to throw the dog 72 into its operative position, seen in Fig. 3, and, 50 when the cam releases the pin, a spring 77 tends to restore the parts to the Fig. 5 position. In this way automatic control of the stitching clutch 64-67 is afforded.

In order to permit the stitching shaft to 55 be turned over by the hand wheel 54 when the machine is not running, a pivoted device 78 may be used, as seen in Fig. 3, which may be swung into the indicated dotted position for the purpose of locking the dog 60 72 in place to prevent the stitching clutch from becoming operative.

Referring now to the clutch for causing the work to jump to and from stitching position when the stitch shaft is not running, this is shown in Figs. 3 to 6, and the

connections therefrom and other details in Figs. 7, 8 and 11.

Loose on the hub 61 of the pulley 60 is an eccentric 80, the hub of which is also loose on the stitching shaft. Surrounding 70 the eccentric is strap 81 having the extension or grip 82, while a spring 83 connects the eccentric and strap and tends to hold the grip against the driving rim 62 of the pulley. When gripped, the pulley is enabled to drive through the clutch to the mechanism to be described.

The control of the clutch 80-83 may be effected by a pair of fingers 84, rigid with the strap, and 85, rigid with the eccentric, 80 similar to the fingers 69 and 70, respectively, of the stitching clutch. Fig. 4 shows the fingers 84, 85 free and the clutch closed, so that all the parts 80 to 85 are rotating with the pulley. Figs. 3 and 5 show these parts 85 stopped.

The clutch connections may consist of a sprocket wheel 86, which is keyed upon the hub of the eccentric 80 and is engaged by sprocket chain 87, extending, as seen in Fig. 90 1, to a sprocket wheel 88 mounted on a short shaft or stud 89, which is also provided with a gear 90, engaging a gear 91 loose on the worm shaft 35. In order that the gear 91 may advance the worm shaft for the 95 jumping movements of the work clamp while permitting the shaft to be advanced otherwise for feeding during stitching, the following clutch or connection may be employed. This comprises an eccentric 92 100 keyed to the worm shaft and engaged by strap 93, having extension or grip 94 engaging the flange or rim of the gear 91. A spring 95 connects the eccentric and strap. By this arrangement, when the clutch 80-83 105 is closed, the strap connections and gear act to advance the worm shaft, but, when the clutch is opened, the parts are idle and the worm shaft is free to be advanced by the intermittent connections from the stitching 110 shaft.

The described clutch 92-95 not only serves to advance the worm shaft during the initial and final movements of the cam disk and work support, but also during the 115 stitching operation serves to prevent any retrograde movement of the worm shaft. This type of clutch locks the shaft against any but forward movement.

I will now describe the control of the 120 clutch 80-83, which causes the jumping movements of the work support when stitching is not proceeding. The two fingers 84 and 85, projecting respectively from the eccentric strap and eccentric, have already 125 been referred to. Fig. 4 shows the clutch operative, and the fingers with the other clutch parts are whirling around counterclockwise with the driving pulley, the stitching shaft 36 being stationary. In Figs. 3 130

and 5; however, the clutch has been rendered inoperative and the jumping movement caused to cease by the action of dog 96, which is shown as standing in the path of 5 the fingers. The action of this device is that the finger 84 first strikes the dog 96, which relatively throws the finger reversely, thus turning the eccentric strap relatively backward and withdrawing the grip 82 10 from the rim 62 of the pulley. This disengagement or ungripping is immediately followed by the complete stoppage of the driven parts by the impact of the other finger 85 against the dog 96. 15 Fig. 3, in fact, shows the fingers 69, 70 stopped by the dog 72 and the fingers 84, 85 stopped by the dog 96, so that both the stitching clutch and the jumping clutch are thrown out of action, the machine being in 20 its final stopped condition.

The dog 96 is in the form of an arm swinging about the same axis as the dog 72, not only for compactness, but for the purpose of a certain joint cam control of the 25 two dogs, as will later appear. The dog 96 is, therefore, of hooked shape, as shown, so as to reach around and take effect at the forward sides of the fingers 84, 85. At the opposite side of its axis of swinging the dog 30 96 is provided with an extension 97, which is pulled downward by spring 98, which spring thereby tends to render the dog effective to release the clutch.

The machine is preferably to be initially 35 started by a finger lever or other member moved at will. Finger lever 99 is shown, which, when depressed, pulls upon rod 100, which, as seen in Fig. 3, is fast on rock shaft 101, which is also provided with rock arm 40 103 connected by upward link 102 with the dog 96. Thereby depressing the finger lever swings the dog from the clutch fingers and permits the clutch spring 83 to assert itself to render the clutch operative, so that the 45 driving pulley will cause the actuation of the sprocket and gear connections to rapidly turn the worm shaft and main cam disk. It is to be understood that the cam disk, when thus initially started into operation, 50 effects the cutting of the buttonhole before causing the jumping forward of the work clamp between cutting and stitching positions.

At the end of the forward jumping movement the operation is to disengage the clutch 55 80-83 and to engage the other clutch 64-67 to put the stitching shaft into rotation for the purposes of stitching and slow feeding. After the completion of the seam, the 60 stitching clutch has to be thrown out and the jumping clutch thrown in again, so as to restore the main cam disk and work clamp to initial position. Therefore, although the finger lever controls the original closing of 65 the jumping clutch, the main cam is required

to effect its subsequent opening and the closing of the stitching clutch, and after that the opening of the stitching clutch, and the reclosing of the jumping clutch, and finally the throwing off of all power when the parts 70 are finally stopped. A convenient joint clutch control from the cam disk or other driven parts may be as follows:

The hub or sleeve which carries the dog 96 and extension 97 is shown in Figs. 3 to 6 75 as having a downwardly extending barrel 104, which contains a sliding pin 105 having a tendency to rise under the influence of spring 106. At certain times the pin 105 is adapted to enter a socket 107 formed directly 80 in a hub or collar 108, which is fast upon the shaft 73 and is located within the hub of the dog 96, which latter loosely surrounds the collar. Initially the pin is disengaged from the socket, as seen in Fig. 3, but, when the 85 dog 96 with its downward extension 104 are swung to the Fig. 4 position, the pin engages the socket, as shown, thereby locking together the two dogs 96 and 72 and the systems of levers, etc., connected with them, so 90 that the subsequent cam control of dog 72, already described, simultaneously controls dog 96.

To disengage the pin 105 from the socket 107 at the end of all operations a slotted 95 arm 109 is shown surrounding the lower or external part of the pin, this arm, as seen in Fig. 6, being a part of a lever which has a downward extension 110 coöperating with a special cam or surface 111 on the main cam 100 disk 23. At the final stoppage of the machine the cam 111 lifts the lever end 110 so as to depress the pin 105 and permit both dogs 72 and 96 to become effective to disengage both of the clutches. 105

The complete operation of the mechanism may be substantially as follows: The parts being initially in the Fig. 3 position, both the stitching clutch and the other clutch are thrown out and the driving pulley 60 is rotating at high speed, but idly, around the stitching shaft 36. The starting of the machine is effected by depressing the finger lever 99. This retracts the dog 96 from the Fig. 3 to the Fig. 4 position. The first result of this is that the spring 83 causes the finger 84 to jump forwardly, as shown in Fig. 4, which immediately engages the grip 82 against the rim 62 of the driving pulley, so that the clutch parts become locked to and 110 rotate with the driving pulley counterclockwise. Also during the retracting movement of the dog 96, the extension 104 is swung to the left so as to enable the pin 105 to enter socket 107, thus temporarily locking together or consolidating the elements surrounding the shaft 73, including the dogs 72 and 96. The rapid rotation of the clutch 115 80-83 with the driving pulley operates through the sprockets and gears and through 120 125 130

the clutch 92—95 to rapidly advance the worm shaft 35, thereby turning the main cam disk 23. The cam disk first operates the slit cutter 26 to cut the buttonhole at a 5 point somewhat to the rear of the needle 24, and thereupon elevates the cutter and promptly shifts or jumps forwardly the work support or clamp from the cutting position to the stitching position. During this 10 operation the dog 72 has been in the position shown in Figs. 3 and 4, thus rendering the stitching clutch ineffective. As soon as the work has arrived at the stitching point, however, the cam surface 76 of the main 15 cam passes from beneath the cam pin 75, which has in the meanwhile sustained the arm 74 rigid with dog 72. The dropping of the cam pin and the arm 74 permits the entire clutch dog system to swing about the 20 shaft 73, this movement being effected by the springs 77 and 98. This combined dog shifting movement serves to throw the dog 72 outwardly and the dog 96 inwardly to the Fig. 5 position, but it will be very clear from 25 Figs. 4 and 5 that the parts are so designed that the dog 96 assumes its effective position in front of the clutch fingers 84 and 85 prior to the time that the dog 72 passes out from engagement with the clutch fingers 69 30 and 70. Momentarily, therefore, both clutches are thrown out. This insures that the jumping feed movement ceases before the stitching shaft and the stitching feed movements are able to commence. The time 35 is practically negligible, since the parts are rapidly swung under the influence of the springs from the Fig. 4 to the Fig. 5 position, but, as stated, the overlapping of operations is prevented.

40 The dog 96, moving into the path of the clutch fingers, abruptly throws out and then stops the sprocket system, which becomes completely idle, while the dog 72, retracting from the stitching clutch fingers, permits the 45 clutch spring to assert itself to render the stitching clutch operative, and thereupon the shaft 36 commences rapid rotation with the driving pulley. This causes the stitching operations to proceed, accompanied by the 50 slow advance of the main cam 23, preferably in an intermittent fashion, so as to properly feed the work during stitching. This condition of affairs continues throughout the stitching of the buttonhole seam. The work 55 is properly guided in a well-known manner, and the stitching devices may be oscillated to carry the seam around the end or ends of the buttonhole. When the end of the seam is reached, the stitching clutch is thrown out 60 and the other clutch thrown in. This is effected by the cam 76 on the main cam disk, which causes the lifting of the pin 75 from the Fig. 5 position to the Fig. 4 position, thus throwing the entire clutch dog system 65 over from the Fig. 5 to the Fig. 4 position.

Again we have assurance against overlapping operations in that the dog 72 is brought into position ahead of the clutch fingers 69 and 70 before the dog 96 is retracted from its effective position. Thereby the stitching 70 clutch is first thrown out of action and the rotation of the stitching shaft abruptly stopped, followed immediately by the jumping clutch asserting itself, it becoming effective to drive the sprockets, gears and 75 worm shaft to turn the main cam disk, thereby shifting the work support back to its initial or cutting position. At the end of this movement the special cam 111 comes into action to swing the lever 109, and thereby pull down the pin 105. Referring to Fig. 4, it will be seen that this results in unlocking the dog 96 from the dog 92, so that the spring 98 is able to swing the dog 96 inward to the Fig. 3 position, where it takes 80 immediate effect to throw out the clutch and bring the parts to an instant stop.

The described mechanism and operation 85 secure the advantages before recited, and other advantages will be apparent to those 90 skilled in the art. Simplicity, effectiveness, and sure and quick action is attained at all parts of the cycle of operations. The improvement insures that the stitching operation will always begin at the same point in 95 the buttonhole, since the work support is invariably brought to exactly the same point when the stitching starts. It insures uniformity in the number of stitches in the buttonhole, and the stitches are invariably led 100 uniformly around the buttonhole. The first or jumping clutch always responds instantly in starting the machine. It is thrown out of action at exactly the right point of time, neither too soon nor too late, so that the 105 jumping movement is bound to cease before the stitching commences. Any possible overlapping of operations is thereby prevented, resulting in avoidance of needle breakage. The same advantage results from 110 the accurate and invariable throwing out of the stitching clutch at the proper point and always prior to the throwing in of the jumping clutch for the final shifting movement of the work, thus again obviating needle breakage. 115

While the clutch devices 44—48 and 92—95 by which the feed shaft 35 is advanced are mere one-way clutches or transmitters of forward motion, the devices 120 64—71 and 80—85 are more than this, each being a clutch-and-stop, capable of being actually disengaged when the connections driven by it are to be stopped. Thus, when the clutch-and-stop 64—71 is opened, it also 125 stops the stitch shaft 36 with the needle out of the work. The entire machine may be summed up in detail as combining a controller, namely, the disk 23 from which the feed is effected, buttonhole cutting mecha- 130

nism 26—27 controlled from said controller, stitching mechanism 24—25, a stitching shaft 36 from which the stitching mechanism is driven, a belt pulley 60 loose on said shaft, 5 a first clutch-and-stop 64—71 between the pulley and shaft adapted when operated to stop said shaft in position with the needle out of the work, a first dog 72 for operating said first clutch-and-stop, connections 38—48 10 from said shaft including a one-way drive clutch for advancing said controller at a speed to cause suitable feed during stitching, a second clutch-and-stop 80—85 actuated from said pulley, a second dog 96 for operating the second clutch-and-stop, connections 86—95 15 from said second clutch-and-stop including a one-way drive clutch for advancing said controller at a quicker speed, a starting means 99—103 for adjusting at will the second dog from operative position to operate the second clutch-and-stop for causing the quicker actuation of the controller and thereby the cutting of the buttonhole and quicker feed of work, automatic connections 20 actuated from the controller for thereafter restoring the second dog to operative position and immediately adjusting the first dog from operative position to operate the first clutch-and-stop for causing stitching accompanied by the slower actuation of the controller, and for thereafter at the completion of the button-hole reversing both dog positions to terminate the stitching and restore the quicker feed of the work, and finally again restoring the second 25 dog to operative position to bring the machine to rest, said controller actuated connections including a device 104—108 for detachably latching together said 30 first and second dogs in such relation that each clutch-and-stop must discontinue driving before the other drives.

The two dogs or members 72, 96, for opening or closing the clutch-and-stop devices, 45 being interconnected and related in action, constitute a duplex clutch governing means, such that when one clutch is driving the throw-in of the other throws out the former, whereby the drive by each must cease as or 50 before the other takes effect when changing speeds, all under the timing control by the cam disk 23; and at the end the dogs are so shifted that neither clutch drives, and the machine is totally stopped.

55 Since many matters of mere arrangement, design, combination, and detail may be variously modified without departing from the novel principles involved in the present improvement, it is not intended to restrict 60 the invention to such features excepting in so far as set forth in the appended claims.

What is claimed is:

65 1. A buttonhole stitching and cutting machine, including in combination, a controller from which the feed is effected, but-

tonhole cutting mechanism controlled from said controller, stitching mechanism, a stitching shaft from which the stitching mechanism is driven, a belt pulley loose on said shaft, a first clutch-and-stop between 70 the pulley and shaft adapted when operated to stop said shaft in position with the needle out of the work, a first dog for operating said first clutch-and-stop, connections 75 from said shaft including a one-way drive clutch for advancing said controller at a speed to cause suitable feed during stitching, a second clutch-and-stop actuated from said pulley, a second dog for operating the second clutch-and-stop, connections 80 from said second clutch-and-stop including a one-way drive clutch for advancing said controller at a quicker speed, a starting means for adjusting at will the second dog from operative position to operate the 85 second clutch-and-stop for causing the quicker actuation of the controller and thereby the cutting of the buttonhole and quicker feed of work, automatic connections actuated from the controller for 90 thereafter restoring the second dog to operative position and immediately adjusting the first dog from operative position to operate the first clutch-and-stop for causing stitching accompanied by the slower actuation of the controller, and for thereafter at the completion of the button-hole reversing both dog positions to terminate the stitching and restore the quicker feed of the work, and finally again restoring the second 95 dog to operative position to bring the machine to rest, said controller actuated connections including a device for detachably latching together said first and second dogs in such relation that each clutch-and-stop 100 105 must discontinue driving before the other drives.

2. A buttonhole stitching and cutting machine, including in combination, a feed means for shifting the work, a constantly 110 rotating power pulley, a first clutch and connections from said pulley for driving the feed means at suitable speed for stitching, a second clutch and connections from said pulley for driving the feed means at 115 a faster speed between stitching and cutting operations, stitching mechanism actuated through the first clutch, cutting mechanism actuated through the second clutch, and a controller automatically controlling 120 said clutches to pass from one to the other and to throw off power at the stopping point.

3. A buttonhole stitching and cutting machine, including in combination, a feed 125 means for shifting the work, a constantly rotating power pulley, a first clutch and connections from said pulley for driving the feed means at suitable speed for stitching, a second clutch and connections from 130

said pulley for driving the feed means at a faster speed between stitching and cutting operations, stitching mechanism actuated through the first clutch, cutting mechanism actuated through the second clutch, and a controller automatically timing said clutches whereby one is thrown off and stopped before the other is thrown on.

4. A buttonhole stitching and cutting machine, including in combination, a feed means for shifting the work, a constantly rotating power pulley, a first clutch and connections from said pulley for driving the feed means at suitable speed for stitching, a second clutch and connections from said pulley for driving the feed means at a faster speed between stitching and cutting operations, stitching mechanism actuated through the first clutch, cutting mechanism actuated through the second clutch, and a controller automatically timing said clutches whereby the first clutch is unclutched and the stitching mechanism brought to a stop with the needle out of the work before the second clutch becomes effective.

5. A buttonhole stitching and cutting machine, including in combination, a power driven rotator mounted in said machine, a feed member, a work holder, connections whereby the feed member causes relative feed movements between the work holder and stitching means, along one route during stitching and along a different route when shifting between stitching and cutting operations, a first clutch-and-stop device actuated from said rotator for driving the feed member at suitable speed for stitching, a second clutch-and-stop device actuated from said rotator for driving the feed member at a faster speed between stitching and cutting operations, stitching means actuated through the first device, cutting means actuated through the second device, and interconnected operating members or dogs for the two devices so related that the drive by each must cease as or before the other takes effect when changing speeds.

6. A buttonhole stitching and cutting machine, including in combination a power driven rotator mounted in said machine, a feed member, a work holder, connections whereby the feed member causes relative feed movements between the work holder and stitching means, along one route during stitching and along a different route when shifting between stitching and cutting operations, a first clutch-and-stop device actuated from said rotator for driving the feed member at suitable speed for stitching, a second clutch-and-stop device actuated from said rotator for driving the feed member at a faster speed between stitching and cutting operations, stitching means actuated through the first device, cutting means

actuated through the second device, and a duplex governing means for said devices such that after a period of driving by one device the throw-in of the other device throws out the former, and automatic control means for timing the successive actions in stitching and cutting a buttonhole.

7. A buttonhole stitching and cutting machine, including in combination a power driven rotator mounted in said machine, a feed member, a work holder, connections whereby the feed member causes relative feed movements between the work holder and stitching means, along one route during stitching and along a different route when shifting between stitching and cutting operations, a first clutch-and-stop device actuated from said rotator for driving the feed member at suitable speed for stitching, a second clutch-and-stop device actuated from said rotator for driving the feed member at a faster speed between stitching and cutting operations, stitching means actuated through the first device, cutting means actuated through the second device, coöperating clutch dogs, one for each device, both actuatable from a single controller and such controller for said dog.

8. A buttonhole stitching and cutting machine, including in combination, a feed member, a first clutch-and-stop device for driving the feed member at suitable speed for stitching, a second clutch-and-stop device for driving the feed member at a faster speed between stitching and cutting operations, stitching means actuated through the first device, cutting means actuated through the second device, and coöperating clutch dogs, one latchable to and unlatchable from the other, a latch means therefor, and automatic control means for actuating one dog and the latch means.

9. A buttonhole stitching and cutting machine, including in combination, a power driven rotator mounted in said machine, a feed member, a work holder, connections whereby the feed member causes relative feed movements between the work holder and stitching means, along one route during stitching and along a different route when shifting between stitching and cutting operations, a first clutch-and-stop device actuated from said rotator for driving the feed member at suitable speed for stitching, a second clutch-and-stop device actuated from said rotator for driving the feed member at a faster speed between stitching and cutting operations, stitching means actuated through the first device, cutting means actuated through the second device, and coöperating clutch dogs, one for each device, both actuatable from a single controller, and timed so that one is unclutched and stopped before the other takes effect.

10. A buttonhole stitching and cutting ma-

chine, including in combination, a first clutch-and-stop device for stitching and feeding, a second clutch and stop device for cutting and quick feeding, a first retractable 5 dog normally holding the first device unclutched and stopped, a second retractable dog normally holding the second device unclutched and stopped, a spring for holding one dog in position and a means operated at 10 will for retracting it to start the machine, means for holding such dog in retracted position latched to the other dog, automatic means for retracting the latter dog and thereby restoring the former to position and 15 subsequently restoring the latter and thereby retracting the former, and automatic means for unlatching the former dog to permit the spring to restore it to position.

11. A buttonhole stitching and cutting 20 machine, including in combination, a stitching shaft, a driving pulley concentric therewith, a duplex clutch device associated with said pulley, a clutch dog retractable to clutch the pulley and shaft, and restorable to unclutch and stop the shaft, slow feeding 25 connections from the shaft, a second clutch dog retractable to clutch the pulley for causing cutting and quick feeding, and restorable to unclutch the same, said dogs being intercon- 30 nectible for harmonious coöperation.

12. A buttonhole stitching and cutting 35 machine, including in combination, a stitching shaft, a driving pulley concentric therewith, a duplex clutch device associated with said pulley, a clutch dog retractable to clutch the pulley and shaft and restorable to unclutch and stop the shaft, slow feeding 40 connections from the shaft, a second clutch dog retractable to clutch the pulley for causing cutting and quick feeding, and restorable to unclutch the same, said dogs being intercon-

nectible for harmonious coöperation and adapted to disconnection for unclutching both clutches.

13. A buttonhole stitching and cutting 45 machine, including in combination, a feed member, a stitching shaft, connections from the stitching shaft for intermittently advancing the feed member at suitable speed for stitching, a device for unclutching and 50 stopping the stitching shaft, and power connections operable when the stitching shaft is idle for advancing said feed member at fast speed, including a one-way driving clutch capable of advancing the feed mem- 55 ber and of preventing back movement thereof during the aforementioned step-by-step feed.

14. A buttonhole stitching and cutting 60 machine including in combination a power driven rotator mounted in said machine, a work holder, means for causing relative feed movements as between the work holder and stitching means along one route during stitching and along a different route when 65 shifting between stitching and cutting operations, a first clutch-and-stop device actuated from said rotator for driving the feed means at suitable speed for stitching, a sec- 70 ond clutch-and-stop device actuated from said rotator for driving the feed means at a faster speed between stitching and cutting operations, stitching means actuated through the first device, cutting mechanism actuated through the second clutch-and-stop device, 75 and a controller automatically controlling said two devices to pass from one to the other and to throw off power at the stopping point.

In testimony whereof, I have affixed my 80 signature hereto.

FRANK ZALESKI.
